UNITED STATES PATENT OFFICE.

HUGO WERNER, OF NEW YORK, N. Y., ASSIGNOR TO ROBERT BEATTIE & SONS, OF SAME PLACE.

DESIGN FOR CARPET.

SPECIFICATION forming part of Design No. 24,847, dated November 5, 1895.

Application filed October 4, 1895. Serial No. 564,674. Term of patent 3½ years.

To all whom it may concern:

Be it known that I, HUGO WERNER, a citizen of the United States, residing at New York city, in the county and State of New York, have invented and produced a new and original Design for a Carpet, of which the following is a specification, reference being had to the accompanying drawing, forming a part thereof, which represents a face view of a carpet in which the new design is embodied.

The invention relates to a design to be worked in or upon surfaces, such as carpets or similar fabrics; and it consists in the novel configuration of figures, as herein shown and claimed.

The design consists of a body A and a border B. The body A is decorated with bunches of flowers of the daisy type, produced

upon a foliage background. In the border B the same style of background and flowers is embodied; but the flowers are arranged between a sub-border of substantially Gre-
cian type and a dado consisting of foliage, figures, and scrolls.

I claim—

1. In the design for a carpet, the body A, substantially as shown.
2. In a design for a carpet, the border B, substantially as shown.
3. The design for carpets consisting of the body A and border B, substantially as shown.

HUGO WERNER.
